UNITED STATES PATENT OFFICE.

PHILIP CAMELI, OF WILMINGTON, DELAWARE.

ADJUSTABLE-SWITCH-POINT RAIL-SECTION.

1,372,935.

Specification of Letters Patent. Patented Mar. 29, 1921.

Application filed October 19, 1920. Serial No. 417,881.

To all whom it may concern:

Be it known that I, PHILIP CAMELI, a citizen of the United States of America, residing at Wilmington, in the county of New Castle and State of Delaware, have invented certain new and useful Improvements in Adjustable-Switch-Point Rail-Sections, of which the following is a specification.

This invention relates to certain new and useful improvements in adjustable switch point rail sections wherein the free ends of the switch points are caused to lie in intimate engagement with the supporting ties so that the wheels of rolling stock in passing thereover will not cause a vibratory movement thereof.

The present invention further relates to improvements over the construction of adjustable switch point rail section shown and described in my patent granted June 22nd, 1920, No. 1,344,259. The construction of adjustable switch point rail section as disclosed in my prior patent has particular reference to tie bar No. 1 to which the free ends of the switch points are connected. An offset extension is carried by each end of the tie bar No. 1 and underlies the base of the adjacent rail while a vertically adjustable plate is mounted on the tie bar extensions and is adjustable by screw bolts threaded through the tie bar extensions to cause the plate to engage the base of the rail with a consequent lowering movement of the tie bar and switch point carried thereby.

The improvement over this construction disclosed in this application embodies a mounting of non-rotatable internally threaded thimbles or bearings within openings provided in the tie bar extension and through which thimbles the adjusting screw bolts are threaded for engagement at their upper ends with the adjustable plate so that should the thimbles or bolts become worn or otherwise damaged, it will be only necessary to replace the thimbles and bolts while the original tie bar No. 1 may be employed indefinitely.

With the above and other objects in view, the invention consists in the novel form, combination and arrangement of parts hereinafter more fully described in connection with the accompanying drawings, and in

which like reference characters indicate similar parts throughout the several views.

In the drawings,

Fig. 1 is a top plan view of a portion of a railway track constructed in accordance with the present invention, tie bar No. 1 being illustrated with the present improvement thereon,

Fig. 2 is a cross sectional view on line II—II of Fig. 3 through one of the rails and a portion of the tie bar No. 1 with a supporting tie for the rails shown in elevation,

Fig. 3 is a top plan view of a portion of one of the rails adjacent tie bar No. 1,

Fig. 4 is a fragmentary plan view of one of the ends of tie bar No. 1 with the adjusting bolt receiving thimbles therein,

Fig. 5 is a sectional view taken on line V—V of Fig. 4,

Fig. 6 is a top plan view of one of the thimbles removed from the tie bar, and

Fig. 7 is a side elevational view of the 75 thimble.

Referring more in detail to the accompanying drawings, there is illustrated a supporting tie 1 of usual construction upon which is mounted the track rails 2 having associated therewith the switch points 3 pivotally mounted in the usual manner and connected adjacent their free ends by tie bars 4 and an end tie bar No. 1 bearing the reference numeral 5. The intermediate portion of tie bar No. 1, as shown in Fig. 1 carries a lateral bracket 6 to which a switch arm 7 is attached for throwing the switch points 3 in an obvious manner.

Detailed construction of tie bar No. 1 bearing the indicating reference numeral 5 is shown in Figs. 2 to 7, the same being of elongated construction having a downward offset extension 8 at each end thereof that underlies the base flanges of an adjacent rail 2 while the switch points 3 are connected to the tie bar adjacent each end thereof, and the offset extension by angle braces 9 secured to the tie bar and the switch point by bolts 10. The switch point 3 rests upon the tie 1 while the offset extension 8 is spaced below the base flanges of the rail 2. A rail engaging plate 11 shown more clearly in Fig. 2 is positioned between the rail 2

and the offset extension 8 and carries depending pins 12 slidably extending through openings 13 in the extension 8 of the tie bar, the pins guiding the plate 11 in its vertically adjusting movements.

To provide for an adjustment of the plate 11 to cause the same to engage the rail 2 for lowering the tie bar No. 1 relative to the supporting tie 1, adjusting screws are associated with the tie bar extensions and plate and embody the provision of sockets 14 in the extension 8 within which are mounted tubular thimbles or bearings 15 carrying oppositely positioned laterally extending lugs 16 and a peripheral edge flange 16' that are countersunk in the upper surface of the tie bar extension as shown in Figs. 4 and 5 to prevent rotary movement of the thimbles relative to the tie bar extension. The thimbles 14 are internally threaded as at 17 and into which the screw bolts 18 are threaded, the upper ends of the bolts extending above the thimbles as shown in Fig. 2 for engagement with the bottom wall of the plate 11 while lock nuts 19 threaded on the bolt engage the bottom wall of the extension 8 to hold the bolts in their adjusted positions.

To provide for a substantially frictional engagement between the switch points 3 and the supporting ties to eliminate all vibratory movement thereof during the passage of rolling stock thereover, the adjusting screws 18 are operated to engage the plate 11 to move the same upwardly into engagement with the base flanges of the rail 2 with a consequent lowering movement of the entire tie bar No. 1 and switch points 3 carried thereby. The practicability of this device will at once be understood when it is realized that should the adjusting screw bolts 18 become worn or damaged or should the threads of the screw and thimble become crossed, it will only be necessary to provide new thimbles and screw bolts while the tie bar No. 1 may be employed indefinitely. The lateral lugs 16 carried by the thimble prevent rotary movement thereof relative to the tie bar. The thimbles 15 are frictionally retained within the openings 14 provided in the tie bar extensions 8 and are so held against vertical movement therein while the lug 16 countersunk in the upper wall of the tie bar extensions prevents rotary movement of the thimbles.

While there is herein shown and described what is believed to be the preferable embodiment of the invention, it is nevertheless to be understood that minor changes may be made in the form, combination and arrangement of parts without departing from the spirit and scope of the invention as hereinafter claimed.

What is claimed as new is:

1. In combination, a pair of switch point rail sections, a tie bar connecting the same,

rail engaging members carried by the tie bar and coöperating devices carried by the tie bar and associated with the rail engaging member to vertically shift said tie-bar to cause a lowering movement of the tie bar 70 and switch points carried thereby, said devices including an adjustable member and a support therefor carried by the tie bar.

2. In combination, a pair of switch point rail sections, a tie bar connecting the same, 75 rail engaging members carried by the tie bar and coöperating devices carried by the tie bar and associated with the rail engaging member to vertically shift said tie bar to cause a lowering movement of the tie bar and 80 switch points carried thereby, one of said coöperating devices being removably carried by the tie bar and supporting the other member thereof that engages the rail engaging member.

3. In combination, a pair of switch point rail sections, a tie bar connecting the same, the ends of the tie bar extending beneath adjacent rails, an adjusting plate supported on each end of the tie bar beneath the rail, 90 adjusting screw bolts threaded through the tie bar engaging the plate to cause the same to contact the rail and lower the tie bar and switch points carried thereby and removable bearings for the screw bolts carried by the 95 tie bar.

4. In combination, a pair of switch point rail sections, a tie bar connecting the same, the ends of the tie bar extending beneath adjacent rails, an adjusting plate supported on 100 each end of the tie bar beneath the rail, adjusting screw bolts threaded through the tie bar engaging the plate to cause the same to contact the rail and lower the tie bar and switch points carried thereby, and internally 105 threaded thimbles carried by the tie bar through which the screw bolts extend.

5. In combination, a pair of switch point rail sections, a tie bar connecting the same, the ends of the tie bar extending beneath adjacent rails, an adjusting plate supported on each end of the tie bar beneath the rail, adjusting screw bolts threaded through the tie bar engaging the plate to cause the same to contact the rail and lower the tie bar and 110 switch points carried thereby, and internally threaded thimbles carried by the tie bar through which the screw bolts extend, said thimbles having laterally extending lugs 115 countersunk in the tie bar to prevent rotation thereof.

6. An adjustable switch point rail section comprising in combination with ties and rails supported thereon, a tie bar having switch points attached thereto with the 125 ends of the tie bar underlying the rails, a vertically adjustable plate supported on each end of the tie bar beneath the adjacent rail, said tie bar having spaced openings therein, internally threaded thimbles fric- 130

tionally received in said openings, oppositely positioned laterally extending lugs carried by the upper ends of the thimbles and countersunk in the upper face of the tie bar ends 5 and adjusting screw bolts threaded through said thimbles for engagement with the adjusting plates to cause the same to engage the rails to lower the tie bar and switch points carried thereby onto the supporting ties.

10 7. In combination, a pair of switch point rail sections, a tie bar connecting the same, rail engaging members carried by the tie bar, means engaging the rail engaging members to move the same into engagement with the 15 rails and removable supports for said means.

8. In combination, a pair of switch point rail sections, a tie bar connecting the same,

rail engaging members carried by the tie bar, means engaging the rail engaging members to move the same into engagement with 20 the rails, and removable supports for said means carried by the tie bar.

9. Means for holding an adjustable switch point in contact with a supporting tie comprising connecting means for switch points, 25 means carried by the connecting means positioned for engagement with rails, means for moving the last named means into engagement with the rails and removable supports for the last named means carried by 30 the first named means.

In testimony whereof I affix my signature.

PHILIP CAMELI.
